UNITED STATES PATENT OFFICE.

ANDREW PAYBERG, OF CHICAGO, ILLINOIS.

PLATE-NUMBERING MACHINE.

1,368,832.

Specification of Letters Patent. Patented Feb. 15, 1921.

Application filed January 2, 1920. Serial No. 348,802.

To all whom it may concern:

Be it known that I, ANDREW PAYBERG, a citizen of the United States, and a resident of the city of Chicago, county of Cook, and 5 State of Illinois, have invented certain new and useful Improvements in Plate-Numbering Machines, of which the following is a specification.

My invention relates to new and useful 10 improvements in plate numbering machines, and has for its object the provision of a plate numbering machine which is simple in structure, economical of manufacture and highly efficient in use.

15 Other objects will appear hereinafter.

The invention consists in the combinations and arrangements of parts hereinafter described and claimed.

The invention will be best understood by 20 reference to the accompanying drawings forming a part of this specification, and in which,

Figure 1 is a longitudinal vertical sectional view of my invention,

25 Fig. 2 is a top plan view of my invention,

Fig. 3 is a sectional view taken on substantially line 3—3 of Fig. 2,

Fig. 4 is a sectional view taken on substantially line 4—4 of Fig. 1,

Fig. 5 is a top plan view of the numbering device used in my invention, and

Fig. 6 is a side elevational view of the numbering device used in my invention.

35 My invention is adapted for impressing numbers on plates used in printing shops. The invention is adapted for impressing numbers upon either electrotype plates, or upon the wood block upon which zinc etchings and halftones are mounted.

The approved form of construction, as 40 illustrated in the drawings, comprises a table or supporting member 9 which is provided at its corners with standards or supporting members in the nature of legs. Extending transversely of the table 9, at the opposite ends thereof, are cross pieces 10 which serve to reinforce the table proper. The table 9 is provided with an elongated

45 slot 11. Adjacent one end of the table and secured thereto by bolts 12, is an abutment block 13. Slidably mounted in the slot 11 is a guide block 14, having laterally extending flanges 15 which engage against the under surface of the table 9 at opposite sides

of the slot 11. Positioned slidably upon the upper surface of the table 9 is a plate 16, formed in which is an elongated slot 17. Projecting through an opening formed in the member 14 and also through the slot 17 60 is a bolt 18 which is threaded at its opposite ends. Threaded upon the upper end of the member 18 is a nut 19 which is provided with a handle 20. Slidably positioned upon the table 9 is a block 21 which has a shoulder 22 adapted to engage in the slot 11. The block 21 is provided with a recess 23 in which is positioned the numbering machine 24. The machine 24 is secured to the block 21 by means of screws 27 which project through orifices formed in ears 26 which are mounted upon the machine 24. The upper surface of the member 21 is provided with recesses in which the ears 26 are adapted to engage so that the same lie flush with the upper surface of the block 21. The machine 24 is provided with a series of numbers mounted upon disks with mechanism for consecutively rotating the disks so as to present the numbers in consecutive order, 70 the rotation taking place upon the pressing of a series block 25. Mounted upon the plate 16 is a pair of lugs 28 which are spaced apart and upon which a lever 30 is pivotally mounted by means of a pin 29. The block 21 is provided with a stud 31 which projects downwardly from the portion 22 and engages in a slot 32 formed in the member 14. As shown in Fig. 1, the lower end of the member 31 is threaded for the reception of a nut 33 and washer 34, being interposed between the nut 33 and the under surface of the member 14. A washer 35 is interposed between the member 19 and the plate 16 and a nut 37 is threaded upon the 80 lower end of the member 18, a washer 36 being interposed between the nut 37 and the block 14. The construction is such that when the parts are assembled upon the member 9, the block 14 is movable along the slot 11, carrying with it the plate 16 and the block 21. The plate 38 upon which the number is to be impressed is positioned in engagement with the abutment block 13 and the plate 16 and the block 14 are 90 moved upon the table 9, until the desired distance between the member 38 and the numbering machine 24 is reached. The members 14 and 16 are then tightly clamped 100 upon the table 9 by means of the nut 19. 110

Upon downward pressure being exerted upon the lever 30, the lower end 39 thereof, which operates as a cam, presses the block 21 forward so as to bring the numbers in 5 the numbering machine 24 into engagement with the member 38. Owing to the cam lever arrangement, great pressure may be brought to bear upon the numbers for impressing them in the plate 38. As shown in 10 Fig. 4, the upper end of the member 18 is provided with an interiorly threaded socket 40 in which is threaded a screw 41, the purpose of which is to limit the downward movement of the lever 30. Positioned upon 15 the member 38 is a collar 42 which is provided with a lug 43, a nut 44 being provided to retain the member 42 in position upon the member 31. A similar collar 45 is positioned upon the member 18, having a 20 similar lug 46. A nut 47 is used for retaining the member 45, in position. A spiral spring 48, the opposite ends of which are connected to the lugs 43 and 46, is provided, the function of which is to withdraw 25 the member 24 from engagement with the member 38 upon the release of the pressure exerted upon the member 31 through the cam 39. As shown in Fig. 6, the member 24 is provided with a dovetailed groove 49, in 30 which a series block 50 may be inserted. In the use of a machine of this class, the plates may be numbered in different series, in which case the member 50 would determine the series. 35 By mounting the numbering device upon the table 9 in the manner described, the plates 38 may be numbered either on the side or on the end. When the plates are to be numbered on the end, the same are laid flat 40 upon the table and the plate 16, with its co-operating parts, is slid on the table 9, until the desired position is reached, when the same is clamped in fixed position. 45 In the use of the machine, it may be desired to number the plate without indicating any special series. To provide for such a contingency whereby the machine may be used without the removal of the member 50 from its assembled position, I have pivotally mounted upon the member 24 a shield 50 55 which may be swung downwardly so as to cover the series letter or number when in use. While I have illustrated and described the preferred form of construction for carrying my invention into effect, this is capable of variation and modification without departing from the spirit of the invention. I, therefore, do not wish to be limited to the

precise details of the construction set forth, but desire to avail myself of such variations and modifications as come within the scope 60 of the appended claims.

Having described my invention, what I claim as new and desire to secure by Letters Patent is:

1. A device of the class described comprising a supporting member; a numbering machine slidably mounted on said supporting member; an abutment block; means for adjusting the position of said machine relatively to said block; and means for moving 65 said machine into engagement with an object positioned intermediate said block and said machine, substantially as described.

2. A device of the class described, comprising oppositely disposed bars; a pair of 70 plates on opposite faces of said bars; a bolt passing through said plates between said bars for clamping the plates thereon; a slide block adjustably mounted with respect to said plates; die-means carried by said slide 75 block on its front face; and cam means carried by said plates for moving the slide block forward, substantially as described.

3. A device of the class described, comprising a pair of spaced bars; a slide block 80 movable freely between said bars; means for clamping said slide block at any desired point along said bars; a second slide block adjustably mounted on said first named slide 85 block; die-means carried by said second slide block on its front face; and cam means carried by said first named slide block for moving the second slide block forward therealong, substantially as described. 90

4. A device of the class described, comprising a pair of spaced bars; a slide block 95 movable freely between said bars; means for clamping said slide block at any desired point along said bars; a second slide block adjustably mounted on said first named slide 100 block; die-means carried by said second slide block on its front face; and a cam lever pivotally mounted on said first named slide block in rear of said second slide block adapted by an operative stroke to force 105 said second slide block forward therealong, substantially as described.

In testimony whereof I have signed my name to this specification in the presence of two subscribing witnesses.

ANDREW PAYBERG.
